UNITED STATES PATENT OFFICE.

HERBERT E. VAN DORN, OF CHICAGO, ILLINOIS.

ELECTRIC COUPLER.

Application filed May 9, 1921. Serial No. 467,798.

My invention has for its object to produce a simple, novel and compact mechanism for automatically coupling together a large number of train circuits on one railway car with those on an adjacent car. A further object of the present invention is to produce a simple and novel electric coupler in which a large number of contacts may be caused to make perfect electrical connection with the contacts of a co-operating coupler and maintain such connection under the usual conditions encountered in railway service.

A further object of the present invention is to produce a simple and novel electric coupler for railway vehicles in which the contact members are effectually housed when the coupler is in uncoupled condition, the housing being automatically opened during the act of coupling to an extent sufficient to permit the co-operating contacts to engage with each other.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a top plan view of a coupler arranged in accordance with the preferred form of my invention, some of the movable parts within the housing being shown in dotted lines, and the coupler being in its uncoupled condition;

Fig. 2 is a front elevation of the coupler as it appears in Fig. 1;

Fig. 3 is a horizontal section following two different planes as indicated approximately by line 3—3 of Fig. 2, the parts being shown in the positions which they occupy when in coupled relation to another coupler;

Fig. 4 is a section taken approximately on line 4—4 of Fig. 3;

Fig. 5 is a side elevation of the coupler in the condition in which it appears in Fig. 3, the outer casing being shown in section; and

Fig. 6 is a section taken approximately on line 6—6 of Fig. 1.

Referring to the drawings, 1 represents a flat, shallow casing open at the front end and at the bottom and closed on the other four sides. The bottom of the casing is closed by means of a detachable plate, 2,

fastened in place by means of screws, 3, or the like. The front end of the casing is adapted to be closed by a door, 4, having rearwardly-extending sides or flanges, 5, at the end, the door with its flanges fitting between the side walls of the casing. The door is attached to the casing by means of suitable trunnions, 6, 6, passing through the wings or flanges, 5, and the side walls of the casing, thus permitting the door to swing from the closed position shown in Fig. 6 to the open position shown in Fig. 5; the side flanges or wings being provided with slots, 7, into which the front end of the closing plate, 2, for the bottom of the casing projects when the door is swung open. The door is normally held closed by means of a spring-pressed rod, 8, slidably mounted in a suitable bearing, 9, in the rear wall of the casing behind one of the flanges or wings of the door; there being a spring, 10, surrounding the rod and bearing at its front end against a collar or shoulder, 11, fixed upon the rod and at its rear end against the stationary bearing member 9. The spring 10 is placed under an initial tension such that, when free to do so, it forces the rod 8 forward far enough to hold the door in its closed position with sufficient pressure to prevent the door from chattering.

Within the casing is a smaller auxiliary casing, 12, also open at the front end and having a large opening, 13, in the bottom; this opening being at some distance from the front end and being normally closed by means of a detachable plate, 14, held in place by screws, 15, or the like. The auxiliary casing is mounted in such a manner that it can move longitudinally in the main casing, without having capacity for movement in any other direction. This may conveniently be accomplished by providing the auxiliary casing with a series of upwardly-projecting ears, 16, there being shown four such ears projecting upwardly from the top of the auxiliary casing near the four corners thereof; and fixing within the main casing a pair of guide rods, 17, 17, each of which extends through two of the ears, the guide rods being parallel with each other and with the longitudinal axis of the coupler. Projecting from the rear end of the auxiliary casing is a large tube or conduit, 18, which passes through the rear wall of the main casing and serves to carry the conductors or cables, not

shown, into the interior of the coupler. The conduit, 18, is made long enough so that it will at no time pass entirely into the main casing, thus preventing the conductors or 5 cables from being rubbed against any part of the main casing as the auxiliary casing moves back and forth.

The auxiliary casing carries the contacts which are normally housed within the main casing but may be projected therefrom after the door is opened, so as to engage with similar contacts in another coupler. In the arrangement shown, there are three rows of contacts arranged one above the other, each 15 row containing eleven individual contacts. The contacts are yieldingly held in a body of insulating material fitting within the front end of the auxiliary casing, each contact being adapted to move longitudinally to a 20 limited extent independently of the other contacts. The body of insulating material in which the contacts are mounted is conveniently divided into a series of individual blocks along vertical longitudinal planes 25 passing through the longitudinal axes of the contacts and thus permitting the body of insulating material to be made up out of a comparatively large number of similar molded blocks so shaped that when they are laid 30 against each other there will be formed between each two consecutive blocks the proper chambers to receive three of the contacts. In the arrangement shown, each contact 35 comprises an approximately square elongated head, 20, arranged upon the front end of a cylindrical stem, 21. The rear end of each stem is screw threaded and carries one or more nuts, 22, adapted to serve as a stop to limit the forward movement of the contact 40 relatively to the supporting body of insulating material. An additional nut or nuts, 23, on the extreme rear end of each of the stems serves the purpose of clamping the end of a wire or other conductor upon the 45 stem. Each of the insulating blocks, 24, is provided in its opposite side faces with recesses so shaped that each recess forms with the corresponding recess in an adjacent block a chamber, 25, in which one of the square 50 heads of a contact piece may slidably fit, this chamber being considerably longer than one of said heads so as to permit a spring, 26, to be placed behind the head around the stem attached thereto; the spring tending 55 constantly to project the head forwardly as far as the nut 22 on the rear end of the stem will permit. The said recesses further produce a cylindrical passage or hole, 27, extending out through the rear of the body of 60 insulating material and having a diameter such that the cylindrical stem of the contact will fit slidably in the same. In order to prevent the conductors attached to the different rows of contacts from accidentally coming 65 into engagement with each other I pre-

fer to give the rear end of the insulating body a step-like formation, making this member deepest throughout the upper one-third thereof, somewhat shallower throughout the middle one-third thereof, and still 70 shallower throughout the lower one-third. The stems on the contacts in the three rows are correspondingly proportioned so that a conductor which hangs vertically from any one of the contacts is clear of the rear end of 75 the contact or contacts below the same. Where there are eleven contacts in each row, there will be ten similar blocks of insulating material, together with two end blocks, 28 and 29, similar to each other but having 80 grooves or recesses in only one face thereof. All of the blocks are preferably flanged at the top and bottom, at the front end, as indicated at 30, so as to limit their entrance into the auxiliary casing. The blocks are 85 preferably fastened into a single body by means of a bolt, 50, passing through the same. After the blocks have been assembled in the auxiliary casing they may be fastened thereto in any suitable way as, for example, by placing a plastic filler between the same and the side walls of the casing as indicated at 31, and by a bolt, 51, passing 90 through the same and through the auxiliary casing. 95

Normally the auxiliary casing, which may be called the contact carrier, occupies the positions illustrated in Figs. 1 and 6, being held in that position by means of a spring, 32, arranged between the front wall of the main casing and an ear, 33, projecting upwardly from the rear end of the contact carrier. This spring is conveniently mounted on a stationary rod, 34, fixed at its ends in the front and rear wall of the main casing and passing freely through the ear 33. When a coupling is to be made between two of my improved couplers, the door at the front of the main casing must be opened and the contact carrier must be projected forwardly against the resistance of the spring 100 32. The door may conveniently be opened by the movement of the contact carrier itself, by causing the contact carrier normally to position itself so far back in the main 105 casing that it is able to move forward, in the act of coupling, through an appreciable distance before the door is fully opened. To this end I have placed on one side of the contact carrier a lug, 35, which projects laterally far enough and at the proper elevation to permit it to engage with the rear edge, 36, of a portion of one of the wings or flanges, 5, lying above the pivotal axis of the door. The parts are so proportioned 110 that when the movable contact carrier starts forward from its position of rest as indicated in Fig. 6, the lug, 35, strikes against the edge, 36, on the door, swinging the door downwardly into its open position against 115 120 125 130

the tension of the spring, 10, which normally holds the door closed. The parts are also so proportioned that after the door has been fully opened and the movable contact carrier projected forwardly to its coupling position, the lug 35 will lie directly over the edge, 36, which then occupies a horizontal position so that the thrust thereof against the lug due to the tendency of the spring 10 to close the door, is vertical, namely at right angles to the direction of movement of the movable contact carrier. The result is that the lug 35 acts as a positive stop or lock for the door so that the thrust of the latter is not transmitted to the actuating or holding means for the contact carrier. It will be seen that when the contact carrier is in its retracted position, the door may be opened and closed manually without affecting the contact carrier, thus permitting the contacts to be examined and inspected at will.

When the contact carrier is moved forward into a coupling position sufficient pressure must be applied to overcome the tension of the spring, 10, which holds the door closed and of the spring, 32, which tends to hold the contact carrier retracted. After the door has been fully opened, the resistance of the spring 10 is eliminated so far as the actuating means for the contact carrier is concerned. However, I prefer to mount the coupler in such a way that after the contacts of two co-operating couplers have been brought into engagement with each other they will be shifted more or less transversely of each other so as to secure a sliding engagement which keeps the working faces of the contacts clean and insures perfect electrical connection. It is therefore necessary for the actuating means for the contact carrier to overcome the resistance of the springs, 26, behind the contacts in order to permit the contacts to be pressed back and insure that the contacts of each pair of co-operating contacts will be in engagement with each other and thus make the wiping action effective. This may conveniently be accomplished by providing each coupler with a plunger adapted to be engaged by the casing of a co-operating coupler, the plunger being connected by suitable means, including a strong spring, with the corresponding contact carrier, the plunger being given a sufficient range of movement to insure that the spring between the same and the contact carrier will be stressed at the end of the coupling operation; and the spring being strong enough to overcome the resistance of the spring, 32, and of the springs 26. In other words, the contacts of two couplers will be forced into engagement with each other and come to rest before the actuating plungers cease their movement and therefore the springs between the actuating plungers and the contact car-

riers will be placed under additional compression or tension, as the case may be, after the movement of the contacts themselves has ceased. Of course, it is not necessary that the springs behind the individual contacts be completely closed during a coupling operation, but my improved construction permits them to be closed if desired. In the arrangement shown, the plunger, 40, is located toward one side of the main casing, 70 projecting through the front wall of the latter, and movable in the longitudinal direction. The inner end of the plunger is attached by means of a link, 41, to one end of a lever, 42, pivotally connected between its ends to the top wall of the main casing as indicated at 43. The free end of the lever 42 lies behind a spring cushion which bears at its front end against an upwardly-projecting flange, 44, on the contact carrier. 75 This spring cushion may conveniently consist of a strong compression spring, 45, loosely surrounding a rod, 46, extending through the flange, 44, and provided at its front end with a head, 47, which prevents it from being drawn backwardly through the flange by means of the spring; there being a suitable head, 48, on the rear end of the rod in engagement with the rear end of the spring; and the head, 48, engaging with the 90 free end of the actuating lever. In Fig. 3 the parts are shown in the positions which they occupy at the end of a coupling operation, the spring, 45, being under compression, while in dotted lines in Fig. 1 the 100 parts are shown in their normal retracted positions.

It is desirable that the contact carrier be brought to rest at a definite point in its forward projection before the actuating plunger has been completely pressed back, thus permitting the spring, 45, to be compressed and hold the carrier firmly in place while the springs behind the contacts are compressed. This may conveniently be accomplished by permitting the flange, 44, on the contact carrier to engage with a shoulder, 49, (see Fig. 6) on the casing when the carrier reaches its extreme forward position.

The relative lateral movement between two couplers may conveniently be obtained by attaching them underneath car couplers of the type illustrated in my prior Patent No. 1,344,780, in which provision is made for bringing about a relative lateral movement 110 between two car couplers toward the end of a coupling operation.

It will thus be seen that I have produced a simple and compact coupler which is normally, when not in coupled relation to another coupler, substantially sealed against the entrance of dirt and moisture; in which the working faces of the contacts may be effectually shielded when two devices are coupled together, by accurately finishing the 125 130

front end of the auxiliary casing and proportioning the parts so that the auxiliary casings of two couplers in coupled relation will fit against each other so as to make a 5 tight joint through which water and dirt cannot penetrate; which will automatically open to expose the contacts in the act of coupling; and which may readily be opened manually both at the front and at the bottom 10 when access is desired to the interior for inspection, repairs or other purposes.

While I have illustrated and described with particularity only a single preferred form of my invention, I do not desire to be limited to the exact structural details thus 15 illustrated and described; but intend to cover all forms and arrangements which come within the terms employed in the definitions of my invention constituting the appended 20 claims.

I claim:

1. In a coupler, a casing open at the front end, a swinging door large enough to extend completely across said open end for closing 25 said open end, a spring acting on said door in a direction tending to hold the same closed, a contact carrier mounted in said casing and adapted to be moved from a position housed within the casing behind said door to a forward position in which the contacts project through said open end, a laterally-projecting lug on said contact carrier, and a part on said door in position to be engaged by said lug to cause the door to swing into its open position as said contact 35 carrier is moved forward.

2. In a coupler, a casing open at the front end, a swinging door large enough to extend completely across said open end for closing 40 said open end, a spring acting on said door in a direction tending to hold the same closed, a contact carrier mounted in said casing and adapted to be moved from a position housed within the casing behind said door to a forward position in which the contacts project through said open end, a laterally-projecting lug on said contact carrier, and a part on said door in position to be engaged by said lug to cause the door to swing into 45 its open position as said contact carrier is moved forward, said part being so positioned with respect to the pivotal axis of the door that the thrust thereof on said lug when the contact carrier is in its forward 50 position, is in a direction transverse to the direction of travel of the contact carrier.

3. In a coupler, a casing open at the front end, a contact carrier arranged within said casing, a plurality of contacts mounted at the 55 front end of said carrier, springs behind said contacts tending to hold them in their forward positions relatively to the carrier, a spring tending to hold said carrier in a retracted position in the casing, an actuator 60 for said carrier adapted to move the latter

forwardly and cause the contacts to project at the front end of the casing, and a spring between said actuator and said carrier of a strength at least as great as the combined strength of all of the other springs.

4. In a coupler, a casing open at the front end, a contact carrier arranged within said casing, a plurality of contacts mounted at the front end of said carrier, springs behind 70 said contacts tending to hold them in their forward positions relatively to the carrier, a spring tending to hold said carrier in a retracted position in the casing, a plunger slidably mounted in the casing and normally 75 projecting beyond the front end of the same in position to be engaged by the front end of the casing of a co-operating coupler, a lever extending transversely of the casing within the same and pivotally supported between its ends thereby, a connection between 80 one end of said lever and said plunger, and a spring between the other end of the lever and said contact carrier, the strength of the latter spring being at least as great as the combined strengths of all the other springs.

5. In a coupler, a casing open at the front end, a body of insulating material arranged within and filling the front end of said casing, a plurality of rows of contacts arranged one above the other in said body of insulating material, springs behind said contacts tending to hold them thrust forward, said body of insulating material being divided into individual blocks along vertical planes defining the longitudinal axes of said contacts, and each of the intermediate blocks having recesses formed in the sides thereof and registering with the recesses in the adjacent blocks to form seats or bearings for 90 said contacts.

6. In a coupler, a main casing having a detachable bottom, and an auxiliary casing slidably mounted therein, contacts supported in the front end of the auxiliary casing in such a manner as to leave a free space in the auxiliary casing behind the contacts, said auxiliary casing having a detachable bottom portion below said space, and a conduit for conductors fixed to the rear end of the auxiliary casing and extending slidably through the rear wall of the main casing, said conduit communicating at its front end with said space.

7. In a coupler, a casing open at the front end, a swinging door for closing said open end, a spring acting on said door in a direction tending to hold the same closed, a contact carrier mounted in said casing and adapted to be moved from a position housed within the casing to a forward position in 110 which the contacts project through said open end, a laterally-projecting lug on said contact carrier, and a part on said door in position to be engaged by said lug to cause the door to swing into its open position as 115

said contact carrier is moved forward, said lug being so positioned on the contact carrier that it lies sufficiently remote from said part on the door when the contact carrier is 5 retracted to permit the door to be manually opened.

8. In a coupler, a casing open at the front end, a contact carrier arranged within said casing, a plurality of contacts mounted at 10 the front end of said carrier, springs behind said contacts tending to hold them in their forward positions relatively to the carrier, a spring tending to hold said carrier in a retracted position in the casing, an actuator

for said carrier adapted to move the latter 15 forwardly and cause the contacts to project at the front end of the casing, a spring between said actuator and said carrier of a strength at least as great as the combined strength of all of the other springs, and a 20 stop on the casing for arresting the forward movement of the contact carrier before the actuator has completed its movement in the direction to project the contact carrier forwardly. 25

In testimony whereof, I sign this specification.

HERBERT E. VAN DORN.
